UNITED STATES PATENT OFFICE.

JOHN TERRANCE FRIEND, OF IRVINE, KENTUCKY.

WEIGHING-SCALES.

SPECIFICATION forming part of Letters Patent No. 399,865, dated March 19, 1889.

Application filed June 9, 1887. Serial No. 240,847. (No model.)

To all whom it may concern:

Be it known that I, JOHN TERRANCE FRIEND, a citizen of the United States, residing at Irvine in the county of Estill and State of Kentucky, have invented new and useful Scales for Weighing, of which the following is a specification.

The main objects of my invention are to provide scales capable of weighing heavy articles without the use of superfluous loose weights, leaving the weighing entirely to the sliding poises, thus saving the time ordinarily expended in the selection of such loose weights and the inconvenience of their frequent loss; also, an arrangement of two graduated beams, whereby tare may be allowed for without the mental process of calculation after every weighing; also, it is my desire to introduce a novel and simple, yet accurate, interior arrangement of levers for the purpose of communicating the weight from the platform to the rod connected with the beams.

Other advantages will be further set forth in the specification, and particularly pointed out in the claim submitted therewith.

In the drawings, Figure 1 is a side view of my improved scales, showing the interior arrangement of the levers in dotted lines. Fig. 2 is a top view of my improved scales with the platform removed, in order to exhibit in detail the arrangement of the internal levers.

Like letters of reference are attached to like parts throughout the drawings.

Within the box A are the levers that support the platform B. The lever C comprises a tongue, C', to the end of which is attached a pair of forks united at their outer ends by the bar c, resting at its two ends in the bearings c' c'. Near the bifurcation of the lever C are placed two upright pins, c². The lever D comprises a frame attached to another cross-bar, d, and corresponding in shape to the forked portion of the lever C. The ends of the cross-bar d rest in the bearings d', attached to the sides of the box in which the levers are placed. The middle of one side of the frame-lever D rests between the two pins on the lever C, as shown in Fig. 2. The extremity of the lever C is attached to the lower end of the upright shaft E of the scales, upon which the scale-pan F is placed. This attach-

ment is pivotal, and is shown in Fig. 1 at E'. The upright shaft E of the scales passes upward through a hollow post, G, to the top of which are attached the arms G'. These arms 55 support the frame of the beams upon the pivots g. These pivots may of course be replaced in the more delicate sorts of scales by the ordinary knife-edges, as shown in Fig. 1. Two short arms extend laterally from a point 60 near the top of the shaft E, as shown at e, and are attached to the frame of the beams at the pivots e'. This pivotal connection may be accomplished by means of arms integral with the shaft E and forming a part of it, or 65 merely attached thereto, or said shaft may be directly pivoted to the beam i, these details being mere modifications of the pivotal attachment of the shaft E to the upper beam.

Between two of the sides of the frame connecting the portions to which the arms G' are attached is a rod, h', upon which slides a weight, H, securable in any desired position upon said rod by means of the screw h. This weight is for the purpose of regulating the 75 scales for various-sized scale-pans, and by its means the weights are kept at zero for empty pans.

Attached to the frame pivoted to the arms G' are the two graduated beams I and I'. 80 The upper beam, I, is made up of two parts, as shown in Fig. 2 at i and i'. To the portion i the frame proper of the beams is attached, and, indeed, a portion of said part i constitutes one of the sides of the rectangle 85 making up such frame proper, and said frame is pivoted to the arm G' on one side through said portion of said part i. The graduated portion i' of said beam I is set off from the portion i, and is furnished with graduations 90 labeled with the proper figures, as will be described hereinbelow. A weight, K, depends from said portion i', and is adapted to slide along said beam for the purpose of balancing the weights in the scale-pan. A bracket 95 depends from the upper beam, I, as shown at I'. This bracket is rigidly attached to said beam I, and bears, by means of an inverted knife-edge, upon the short arm of the beam I'. Said beam I' is pivoted to a bracket attached 100 to the box, as shown at L, and its free or longer arm plays within a slot in a down-

wardly-projecting check-arm, L'. A weight, M, also hangs upon this lower beam, and is adapted to slide upon said beam and mark the graduations which appear thereupon for the purpose of counterbalancing the weights put into the pan.

Both of the beams are graduated in two lines, as shown, one of said lines placed below the other. The upper row of figures represents the loads which when put into the scale-pan will counterbalance the weight when brought over said figures, and the lower row of figures represents the loads which are put onto the platform under the same circumstances.

It is evident on inspection of the arrangement of the beams and weights that they can be so calculated that when the scale-pan is empty and the upper weight is in the position shown in Fig. 1 at zero the lower weight will just hold the lower beam even and on the same level when at the zero. Under these circumstances the end of the lower beam will touch neither the bottom nor the top of the check-slot within the bracket L'. Now if a load be put into the scale-pan or onto the platform, so as to depress the shaft E, it is evident that said shaft will act through the arms e to depress one side of the frame bearing the beams. In this movement the upper weight, K, when at zero, as shown in Fig. 1, acts to aid the weights in the scale-pan, and the only agency tending to counteract this twofold action of depression is the weight M on the lower beam. This weight, therefore, can be moved outward until the depressing tendency of the scale-pan's contents and the upper weight are counteracted, when the figures directly under the bail by which said lower weight is hung will indicate the weight of the article in the scale-pan. When the weight M on the lower beam has been carried out to its fullest extent, and it still does not counterbalance the weights in the scale-pan or on the platform, the upper weight can be brought into requisition, and by being moved farther to the right, as shown in Fig. 1, the aid which it affords to the downward tendency of the shaft E be lessened until the lower beam balances, when the sum of the indications of the two beams will evidently be the weight acting upon the shaft E.

Where goods are being weighed in boxes,

or where other tare must be allowed for, the simplest mode of allowance will be to place the upper weight permanently at such a figure on the upper beam as indicates this allowance, and then proceed to weigh the goods in the boxes. This is supposing all the boxes in a given shipment or consignment to be of the same weight, which is frequently the case.

The action of the platform upon the levers will need but slight additional explanation. The legs b on the lower side of the platform are provided with grooves, which rest upon the pins c³ on the sides of the levers C and D. The distances of these pins from the bearings c' and the point of bearing of the lever D upon the tongue of the lever C being equal, respectively, it is evident that however the weights are disposed upon the platform the same effort will be exerted, and with the same diminished leverage at the shaft E. The well-known effect of compound levers, in which the weight acts through smaller lever-arms throughout the system, comes into play here, and by a very simple arrangement the maximum accuracy and leverage in the advantageous sense are secured by my invention.

Having thus described the construction, advantages, and mode of operation of my invention, what I believe to be new therein, and what I therefore claim, is—

In scales, the lower beam pivoted at L and graduated away from said pivot, and having a short arm on the side of the pivot away from said graduation, the upper beam connected with said lower beam by a bracket-arm, I², at the short arm of said lower beam, the standard G, to which said upper beam is pivoted, and the shaft E, pivotally attached to said upper beam, in combination with the lever C, resting at one end in the bearings c', and attached at its other end to the bottom of said shaft E, and provided with pins c³, the lever D, resting in the bearings d', pressing at its other end upon a point upon the lever C, and provided also with pins c³, and the platform B, provided with the legs b, bearing upon the pins c³, substantially as specified.

JOHN TERRANCE FRIEND.
